CLAIM

The ornamental design for a charging pad, substantially as shown and described.

DESCRIPTION

FIG. 1 is a front, top, right perspective view of a charging pad of our new design;

FIG. 2 is a rear, top, left perspective view of FIG. 1;

FIG. 3 is a front elevational view of FIG. 1;

FIG. 4 is a rear elevational view of FIG. 1;

FIG. 5 is a left side elevational view of FIG. 1;

FIG. 6 is a right side elevational view of FIG. 1;

FIG. 7 is a top plan view of FIG. 1; and,

FIG. 8 is a bottom plan view of FIG. 1.

The relatively light and thin shade lines shown in the drawings are included for the purpose of indicating surface contour and not surface decoration.

The broken lines in the drawings illustrate portions of the article that form no part of the claimed design.
